UNITED STATES PATENT OFFICE.

ANGUS K. CAMPBELL, OF NEWTON, IOWA.

APPARATUS FOR HEATING AND VENTILATING ROOMS.

SPECIFICATION forming part of Letters Patent No. 275,585, dated April 10, 1883.

Application filed September 30, 1882. (No model.)

To all whom it may concern:

Be it known that I, ANGUS K. CAMPBELL, a citizen of the United States, and a resident of Newton, in the county of Jasper and State of Iowa, have invented a new and valuable Improvement in Methods of Heating Houses, &c.; and I do hereby declare that the following is a full, clear, and exact description of the construction and operation of the same, reference 5 being had to the annexed drawing, making a part of this specification, and to the letters and figures of reference marked thereon.

The figure of the drawing is a sectional view of a dwelling with my apparatus applied thereto.

15 This invention has relation to an improvement on the means for heating and ventilating houses described in the specification attached to Letters Patent No. 230,237, granted to me on the 20th day of July, 1880.

20 The objects designed to be attained by the present invention refer to the saving of fuel, to securing a constantly-moistened air, to the prevention of overheated air, and to the maintenance of a constant temperature.

25 In carrying out this invention a heating-room, A, is designed to be built in the basement or on the first floor of the house. This room may vary in size somewhat, but for ordinary purposes may be made six feet wide by 30 eight or ten feet long with excellent results.

Within this heating-room is placed the furnace or heater B, which may be of any suitable character—for instance, a steam-heater, hot-water heater, furnace, or other heat-generator.

35 The heater is considerably smaller than the heating-room in which it is placed, the walls of said room being not designed to act as a close jacket around the heater, but being sufficiently distant therefrom to avoid the power- 40 ful effect of the radiation.

C C represent flues or ducts which lead from the floors of the apartments to be warmed and ventilated down to the heating-room A. These flues are designed to discharge the air drawn from the lower portions of the rooms above into the lower part of the heating-room.

45 D D represent ventilating-flues, which are located with their mouths opening at or near

the bottom of the heating-room, whence they conduct the air which lies lowermost in the 50 heating-room into the heater and smoke-flues, thus drawing off a sufficient quantity of air to secure the purification of that which passes through the heating-room. Any accumulation of foul air is effectually disposed of through 55 the action of the heater and smoke-flues.

A ventilating-pipe, E, extending to the outside atmosphere, admits into the heating-room a supply of fresh air at a point or points where it will be immediately heated and pass into 60 the rooms to be warmed, the supply being regulated by dampers under the control of the occupants.

Warm-air ducts F lead from the top of the heating-room to the apartments to be warmed. 65

Within the heating-room is placed in suitable reservoirs, G, a considerable quantity of water, ordinarily from twenty to thirty cubic feet. The reservoirs or receptacles G are constructed with ample radiating-surface, and 70 the water is designed to be heated by the fire of the heater to 175° or 200° of Fahrenheit. The water-battery is constructed so that a constant circulation of water is maintained therein, the surface of the water being exposed 75 sufficiently to moisten the air of the building while the same is passing through the heating-room. Valves or adjustable covers for the openings of the water-battery may be provided, so that the exposure of water-surface 80 may be under the control of the occupants of the house. The heating-room is designed to be air-tight at all points, with the exception of the flues and ducts described, which form its members, whereby it is enabled to maintain a constant circulation of warmed and ventilated and purified air throughout the house. The movement is constant so long as the heater is in operation. The air is maintained in a suitable moist condition for breathing and at a constant temperature.

Having described this invention, what I claim, and desire to secure by Letters Patent, is—

1. The combination, with the heating-room 95 A, of the heater B, flues C D, ventilating-pipe

E, and warm-air ducts F, substantially as specified.

2. The combination, with the heating-room A, of the heater B, flues C and D, ventilating-pipe E, warm-air ducts F, and the water-battery within the heating-room, substantially as specified.

In testimony that I claim the above I have hereunto subscribed my name in the presence of two witnesses.

A. K. CAMPBELL.
